UNITED STATES PATENT OFFICE.

WILLIAM M. TALBOTT, OF NEW YORK, AND JAMES C. LEDBETTER, OF BROOKLYN, NEW YORK, ASSIGNEES, BY MESNE ASSIGNMENTS, TO UNITED STATES HOFFMAN MACHINERY CORPORATION, OF NEW YORK, N. Y., A CORPORATION OF DELAWARE.

PRESSING MACHINE.

Application filed December 22, 1921. Serial No. 524,102.

This invention relates to garment pressing machinery, and more particularly to improvements in high pressure presses; and has as its primary object that of producing 5 a pressing machine operated, as by foot power, to produce a high degree of compression upon the article being pressed and treated.

In garment manufacturing plants it is 10 the usual practice to employ high powered pressing machines to shape garments and finish heavy and thick garment seams; and for this work power pressing machines have been devised, as for example the machines 15 shown in Patents 1,379,601, 1,386,665 and 1,291,222. These high powered pressing machines utilize electricity, air pressure, or steam, for developing the necessary power for operating the machines at high pressure, 20 and such machines are expensive to manufacture, and entail an operating and upkeep cost which is one of the purposes of our invention to eliminate. Another Patent 1,069,232 shows a pressing machine employing 25 double means for working the pressing members, and it is a manually operated machine, but the arrangement of operating means is such as to not provide a smooth, easy, quiet foot power machine which a press 30 operator can rapidly work by foot power.

It is fitting, therefore, that the primary object of our invention is to provide improvements in garment pressing machines to the end that high pressure is obtained by 35 an operator operation so as to dispense with the use of electric and steam power; and it is also an object to produce a machine simple in construction, comparatively inexpensive to manufacture, one having few 40 working parts, and a machine which is unlikely to get out of working order.

It is also an object to produce an improved 45 pressing machine which has a closing means and high pressure producing means, each of which may be adjusted relatively to the other so as to equally divide, if desirable, the total effort of the operator, between the two said means; and to produce a press which opens quietly without jar or strain; 50 and to produce a press capable of two uses, namely, edge and seam heavy pressing and light finish pressing work.

A pressing machine constructed in accord-

ance with the plans of this invention embodies an arrangement of double pedals 55 with a closing toggle and a power toggle, one pedal being employed to close the press to produce initial pressure, and the other pedal being used to produce final heavy pressure on the garment edge or other object 60 being pressed and finished; and in addition, there are improvements in the arrangement of the operating parts, and the provision of features to make the press quietly open and close without undue effort and strain either 65 on the operator or the machine.

The accompanying drawings illustrate one embodiment of our invention, and though there is shown one preferred form of construction and mode of operation, we claim 70 a right of protection as to such changes as obviously come within the scope of the invention.

In the drawings, Figure 1 illustrates a 75 side view of a pressing machine embodying the principles of this invention, the near side of the frame being removed to expose the working parts. The press is in closed position under initial or light pressure; but the press head is shown in dotted lines 80 as being open.

Figure 2 illustrates the press in side elevation, closed under final pressure, with both operating pedals in downwardly limited position.

Figure 3 shows a cross-sectional view 85 taken on the line 3-3 of Figure 2; and Figure 4 shows a sectional view taken on the line 4-4 of Figure 2.

Referring now more in particular to the drawings, for a detailed description, there is shown a frame 8 with rear upstanding brackets 9. The frame comprises two spaced frame webs 8 within which the operating parts are installed to produce a compact machine of refined appearance. The frame supports a work support or buck 10, and a press lever 11 is fulcrumed at 12 between the frame brackets 9, and on the front end of the press lever there is mounted 100 a pressing head 13. A pair of pedals or levers is employed for swinging the press lever 11 to close the head 13, followed by the production of high compression between the head and buck; and the arrangement of the two pedals with link and toggle con-

nections with the press lever permits an operator to produce extremely high compression upon the work support.

A toggle comprising links 16 and 17 is pivoted at 18 on the rear end of the press lever; and the lower end of this toggle is connected to the short arm 19 of a bell crank 20, which bell crank is fulcrumed in the frame on a pin 21. A short vertical motion is imparted to the straightened vertical toggle 16-17 by swinging rearwardly the long vertical arm 20 of bell crank, and this action produces final high pressure on the work support 10 subsequently to closing the head 13 on the buck 10. The top link preferably is provided with an adjusting head or nut 14 which, when turned, varies the overall length of the vertical toggle, to increase or decrease the closing initial pressure of the press head 13 on the work support; and the effort required to push down the closing pedal is variable in accordance with the setting or adjustment of the nut 14.

A closing toggle comprising links 23 and 24 has its rear end pivoted to the vertical toggle at 25, and its front end pivotally anchored to the frame on the pin 26; and the arrangement of this toggle is such that when straightened there is imparted to the vertical toggle a straightening action so that the toggles 16-17 and 23-24 approach a substantially transverse position one to the other. A closing or initial pressure pedal 27 is pivoted in the frame on a pin 28, and the pedal has a foot piece 29 by which the operator depresses it. This pedal is connected to the closing toggle 23-24 by a link 30. Thus by depressing the pedal 27 both sets of toggles, as aforesaid, are straightened to close the head onto the buck.

A high pressure toggle is employed to actuate the bell crank 20, and consists of links 32 and 33, having their adjacent ends pivoted together. The rear link 32 is connected to the bell crank at 34, and the front link 33 is pivotally anchored to the frame as on the pin 26. The link 32 is adjustable, and is constructed in the form of a threaded rod which may be rotated to slightly vary the overall length of the toggle 32-33, in order that the position of the bell crank may be slightly altered to vary the final compression between the head and buck. A high pressure lever or pedal 36 with foot piece 29 is pivoted in the frame, as on the pin 28; and a link 37 connects this pedal with the high pressure toggle 32-33. When this pedal is thrust downwardly the toggle is straightened to force rearwardly the long arm of the bell crank which lifts the vertical toggle through a short distance to impose additional force upon the press lever and head to increase the compression between the pressing members 10 and 13.

Thus it is seen how the first pedal 27 is

depressed to bring the pressing head into engagement with the buck; and by pushing the other pedal 36 to downwardly limited position, the press lever 11 is moved slightly on the fulcrum pin 12 to impose additional high pressure on the buck 10. The link 37 may be turned to adjust the relation between a pedal and its respective toggle, so that when the pedal is in downwardly limited position, the toggle will have reached a straight line and locked position so as to maintain this place under pressure.

A release or kick-off device in the form of a pedal 39 is pivoted at 40 on the frame and has a rear lifting end embodying a high contact surface 41 and an adjacent low contact surface 42. The rear end of the pedal 39 is disposed directly underneath the pedals 27 and 36; and the arrangement of the release or kick-off pedal is such that the stepped contact surface 41 first engages the pedal 36 to impart an upward thrust thereto, and thereafter engages the pedal 27 to produce a similar upward thrust thereon; and it is seen, therefore, how, when the operator steps on the release pedal 39, the two operating pedal levers are, one at a time, forced upwardly. And in this arrangement, the high compression is first spent or dissipated, followed immediately by the lifting of the head 13. It is desirable to thus arrange the kick-off pedal 39 so that the stored up energy and pressure is gradually spent or dissipated as distinguished from lifting the press head 13 before the press gains relief from the high pressure.

A pressing machine of this type which works under abnormally high pressure necessarily requires means for absorbing the shock of the moving parts in order that the machine will not be subjected to strain when coming from under high pressure; and to accomplish this purpose, an air cushion device is employed which comprises a dash pot 44 pivotally anchored at 45 to the frame; and a connecting rod 46, with a piston confined in the cylinder, is attached to the high pressure pedal 36. The compression of the air confined in the cylinder imposes yielding resistance to the upward thrust of the pedal and thus absorbs the shock of the suddenly moving parts, so that the release of the machine from high pressure is accomplished quietly and smoothly without noise or damage to the mechanism. A coil spring 47 is applied to each pedal to lift and support it in uppermost position; and to this end the springs have their upper ends anchored to the frame and their lower ends are fastened respectively to each pedal.

In the operation of the machine, the operator spreads the garment and seam, or the object to be pressed, over the surface of the buck, and then thrusts downwardly the closing pedal 27. This action brings both tog-

gles 23—24 and 16—17 into straight line position which swings the press lever 11 and engages the head 13 onto the garment under initial closing pressure. The operator next 5 pushes downwardly the high pressure pedal 36 which straightens the toggle 32—33 and forces rearwardly the bell crank arm 20 to lift upwardly the vertical toggle, and this action imposes additional pressure on the 10 head 13 to produce a high degree of compression against the object being treated and pressed. To open the press, the pedal 39 is thrust downwardly, which first kicks off the pedal 36 to break the high pressure toggle 15 32—33 and thus slightly lower the vertical toggle 16—17, which action releases the machine from high pressure. The dash pot 44 absorbs the shock and strain as the pedal 36 swings upwardly. As the kick-off pedal 39 20 is forced further downwardly, the pedal 37 rises to break the closing toggle 23—24 which swings the lever 11 and lifts the head off the work.

Inasmuch as two pedals are provided for 25 producing the extraordinary high pressure, it follows that the effort or work done by the operator may be beneficially and equally divided between both pedals so that one pedal operates under about the same exerted effort 30 as the other. If desirable, the operator can adjust the initial closing pressure by turning the nut 14 so as to make the head 13 close very easily; and thereafter it is necessary to rotate the adjustable link 32 until the high 35 pressure toggle is made considerably longer in order that the bell crank arm 20 may be forced further out to the rear to lift the vertical toggle somewhat higher to impose adequate additional pressure upon the head 40 13. However, it is preferable to so set the adjustment parts 14 and 32 that both pedals 27 and 36 work with about equal effort in order that the operator will not be required to exert, at one time, little effort, and at another time, greater effort.

In the pressing and finishing of manufactured clothing and garments, it is the usual practice to employ very high pressure to flatten and shape the seams, and thereafter 50 to use light finishing soft pressure to finish off the garment and impart to the fabric a refined nap raised finish. It is common practice to employ two presses for this work so that the heavy edge pressing is done upon 55 one type of machine and the finish pressing is done on another machine. A particular advantage of the present invention is that it provides a two purpose press which can be used for both aforesaid purposes; and to this 60 end the operator may use both pedals to do heavy edge work, and thereafter use the closing pedal to do light finish pressing work.

This machine embodies specific advantages 65 over various other types of high powered edge presses in that it produces as much

pressure as motor and steam operated machines without the cost of upkeep and power and without the great cost of manufacture of motor driven and steam powered presses.

In addition to the above, this pressing machine is simple to operate and is unlikely to get out of working order because of the absence of electric control mechanism, or steam or fluid pressure control mechanism.

Having described the invention, what we claim is:

1. A pressing machine comprising pressing members movable one in relation to the other to effect an opening and closing motion of the press, a pedal actuated connection established with one pressing member for closing the press under initial pressure, and another pedal actuated connection also operative in conjunction with said pressing member for producing final high pressure between the closed pressing members, said pedals standing adjacent each other and having substantially the same range of movement.

2. A pressing machine comprising relatively movable pressing members which open and close on the article to be pressed, a pair of pedals arranged in parallel relation and having substantially the same range of movement in order that they may be conveniently worked by an operator, a toggle connection arranged between one pedal and a pressing member to close the press when this pedal is depressed, and a toggle connection established with the other pedal and said pressing member for imposing high pressure on the closed press.

3. A pressing machine embodying press elements which close against the article being pressed, a pair of operating levers adapted to move in one direction to close the elements and produce pressure therebetween, means, including a connection established between each operating lever and a press element, whereby one lever may be actuated to close the press and the other lever thereafter actuated to produce pressure between the closed press elements, a release device which co-operates with both levers to first move one lever in its reverse direction to relieve the machine from high pressure and subsequently engage and move the other lever in its reverse direction to open the press.

4. A pressing machine embodying press elements which close against the article being pressed, a pair of operating levers adapted to move in one direction to close the elements and produce pressure therebetween, means, including a connection established between each operating lever and a press element, whereby one lever may be actuated to close the press and the other lever thereafter actuated to produce pressure between the closed press elements, a

release device which co-operates with both levers to first move one lever in its reverse direction to relieve the machine from high pressure, means arranged to impose yielding resistance upon the reverse movement of the lever to effect an easy and quiet release of the elements from high pressure, and the said release device adapted to subsequently engage and move the other lever in the reverse direction to open the press.

5. A pressing machine embodying press elements which close against the article being pressed, a pair of operating levers adapted to move in one direction to close the elements and produce pressure therebetween, means, including a connection established between each operating lever and a press element, whereby one lever may be actuated to close the press and the other lever thereafter actuated to produce pressure between the closed press elements, a release device which co-operates with both levers to first move one lever in its reverse direction to relieve the machine from high pressure, a dash pot attached to this lever to retard the reverse movement of this lever, to effect an easy and quiet relief of the machine from high pressure, and the said release device adapted to subsequently engage and move the other lever in the reverse direction to open the press.

6. A pressing machine comprising pressing members movable one in relation to the other, a pair of pedals arranged in parallel relation, a pair of toggles similarly arranged in parallel relation and disposed above the pair of pedals, a link connecting each pedal with a toggle so each pedal independently works one toggle, a means forming a connection between one toggle and a pressing member to move one member into engagement with the other when one pedal is depressed, and a means connected with the other toggle and with said pressing member to impose high pressure when the other pedal is depressed.

7. A pressing machine comprising a work support, a swinging press lever carrying a press head to engage the work support when the lever reaches an approximately horizontal position, a toggle connected with the press lever, a second toggle connected with the first named toggle, a pedal having connection with the second toggle and acting to straighten the second and first toggle to cause the press head to contact the work support with a relatively light pressure when the pedal is actuated, a third toggle, a second pedal having connection with the third toggle, and means related with the third toggle for imposing high pressure onto the press lever and head when the second pedal is actuated.

8. A pressing machine comprising a work

support, a swinging press lever carrying a press head to engage the work support when the lever reaches an approximately horizontal position, a toggle connected with the press lever, a second toggle connected with the first named toggle, a pedal having connection with the second toggle and acting to straighten the second and first toggle to engage the press head and work support when the pedal is actuated, a third toggle, a second pedal having connection with the third toggle, and a bell crank having one arm connected to the third toggle and the other arm connected with the first toggle to impart a short movement of great force through the first toggle onto the press head when the second pedal is actuated.

9. A pressing machine comprising a work support, a swinging press lever carrying a press head to engage the work support when the lever reaches an approximately horizontal position, a toggle connected with the press lever, a second toggle connected with the first named toggle, a pedal having connection with the second toggle and acting to straighten the second and first toggle to engage the press head and work support when the pedal is actuated, a third toggle, a second pedal having connection with the third toggle, and means related with the third toggle for imposing high pressure through the press lever and head when the second pedal is actuated, and a third pedal acting as a release device arranged alongside of the first and second pedals adapted when depressed to first lift the second pedal to relieve the press of high pressure and subsequently lift the other pedal when further depressed to cause the press head to lift off the buck.

10. In a pressing machine the combination of a fixed pressing member; a movable pressing member; a lever to one end of which said last named member is attached; a toggle connected to the lever and acting, when straightened, to swing the lever and bring the pressing elements into pressing relation; a toggle serving to straighten the first named toggle; a lever for actuating the last named toggle; a second lever; and a third toggle actuated thereby, said third toggle when straightened acting to apply thrust to the first named toggle when the same is in its straightened position and to thereby increase the pressure between the pressing members.

11. A pressing machine comprising a work support, a swinging press lever and head which closes on the work support, a bell crank having a long vertical arm and short horizontal arm, a member supported on the short bell crank arm and connected with the press lever and ranging substantially parallel to the bell crank, a toggle connected with the bell crank, and a pedal to straighten

the toggle to actuate the bell crank to impose final force on the head.

12. A pressing machine comprising a work support, a swinging press lever and head which closes on the work support, a bell crank having a long vertical arm and short horizontal arm, a member supported on the short bell crank arm and connected with the press lever and ranging substantially parallel to the bell crank, a toggle connected with the bell crank, and a pedal to straighten the toggle to actuate the bell crank to impose final force on the head, a trip device which thrusts upwardly on the pedal to break the toggle, and an air cushion means to retard the upward movement of the pedal to produce a smooth opening action of the press.

13. A pressing machine comprising relatively movable pressing members which open and close on the article pressed, a pair of levers, said levers having substantially equal distances of travel, a connection established between one lever and a pressing member in such a manner that the press closes when the lever is moved thru its operating distance, a link connection formed between the other lever and said pressing member whereby the member is forced against the other pressing member by moving the last named lever through an operating distance substantially equal to that of the other lever.

14. A pressing machine comprising relatively movable pressing members which open and close thru a suitable distance of movement so as to leave adequate open space to receive the article being pressed, a pedal connected with a pressing member adapted to move the member thru its closing distance by one stroke of said pedal, and another pedal connected with said pressing member and adapted to move the member thru a short range of movement to produce high pressure between the pressing members, the arrangement being such that both pedals have substantially equal strokes.

15. A pressing machine comprising pressing members movable one in relation to the other, a pair of pedals arranged in parallel relation, a pair of toggles similarly arranged in parallel relation and disposed above the pair of pedals, a link connecting each pedal with a toggle so each pedal independently works one toggle, a means forming a connection between said toggle and a pressing member to move one member into engagement with the other when one pedal is depressed, means connected with the other toggle and with said pressing member to impose high pressure when the other pedal is depressed, and a release device arranged to lift one pedal to first relieve the machine

of high pressure and to then lift the other pedal to open the press.

16. A pressing machine comprising pressing members movable one in relation to the other, a pair of pedals arranged in parallel relation, a pair of toggles similarly arranged in parallel relation and disposed above the pair of pedals, a link connecting each pedal with a toggle so each pedal independently works one toggle, a means forming a connection between one toggle and a pressing member to move one member into engagement with the other when one pedal is depressed, a means connected with the other toggle and with said pressing member to impose high pressure when the other pedal is depressed, a release device arranged to lift one pedal to release the machine from high pressure, a cushion means to retard the release of the machine from high pressure, said release device acting further to impart a lifting force against the engaged pressing members, and a tensioning member to complete the operation of disengaging the member.

17. A pressing machine comprising relatively movable pressing members, a pair of pedals, a toggle and link connection established between each pedal and a pressing member whereby one pedal brings the members into engagement and the other pedal produces increased pressure between the engaged members, a third pedal having a foot piece and a rear lifting end which end is positioned directly under and in alignment with the aforesaid two pedals, said rear lifting end having a high and low contact surface, and the arrangement being such when the operator depresses the foot piece that the high contact surface lifts one pedal to relieve the press of high pressure and then lifts the other pedal with the low contact surface to separate the pressing members.

18. A pressing machine comprising relatively movable pressing members, a pair of operating pedals to open and close the press, means, including a connection established between each pedal and a pressing member, whereby one pedal may be actuated to close the machine under pressure, and the other pedal actuated to increase the pressure as produced by the first pedal, and an adjustment means related with each connection whereby the total effort necessary to work the press may be equally divided between the two pedals.

In testimony whereof we have hereunto affixed our hands this 21st day of December, 1921, in the city of New York, county and State of New York.

WILLIAM M. TALBOTT.
